UNITED STATES PATENT OFFICE.

ALFRED D. MOSBY, OF CHICAGO, ILLINOIS, ASSIGNOR TO MARSH-CAPRON MANUFACTURING COMPANY, OF CHICAGO, ILLINOIS, A CORPORATION OF ILLINOIS.

APPARATUS FOR DISTRIBUTING CONCRETE.

1,222,016.

Specification of Letters Patent. Patented Apr. 10, 1917.

Application filed January 18, 1915. Serial No. 2,890.

To all whom it may concern:

Be it known that I, ALFRED D. MOSBY, a citizen of the United States, residing at Chicago, in the county of Cook and State 5 of Illinois, have invented certain new and useful Improvements in Apparatus for Distributing Concrete, of which the following is a specification.

My invention relates to an apparatus for 10 distributing concrete, or such like material, and the principal object of the invention is to provide an apparatus adapted to receive concrete from a concrete mixer and mechanically distribute the same, for example, in street paving work, over a considerable 15 area, thereby doing away with the necessity of transporting the concrete in batches to the places where required by the use of wheel barrows, or the like, which has heretofore been ordinarily practised in work of 20 this sort.

The invention consists in the novel devices, combinations and constructions, to be hereinafter described and claimed, for carrying out the above object and such other 25 objects as will appear in the following description of the invention.

The drawings appended hereto illustrate the invention in a preferred embodiment 30 and additionally show certain possible modifications. In the drawings—

Figure 1 is a side elevation of the preferred apparatus, the drawings showing only a portion of the supporting truck and 35 of the concrete mixing drum.

Fig. 2 is a detail elevation of the outer or discharge end of the distributing trough;

Fig. 3 is a vertical sectional view taken on line 3—3 of Fig. 1.

40 Figs. 4, 4^a, which should be read together, show the apparatus in longitudinal section, the section line being indicated at 4—4 on Fig. 3, Fig. 4 showing the inner end of the distributing trough and the parts of the apparatus associated therewith, and Fig. 4^a the outer end of the trough.

Fig. 5 is a vertical sectional view taken on line 5—5 of Fig. 4^a.

Fig. 6 is a plan view, with certain parts 50 in section, of the inner end of the distrib-

uting trough, the feed hopper therefor and adjacent parts of the apparatus.

Fig. 7 is a fragmentary view, partly in elevation and partly in section, illustrating a modified form of apparatus. 55

Fig. 8 is a similar view illustrating another modification.

Like characters of reference designate like parts in the several figures of the drawings.

Referring first to Figs. 1 to 6 inclusive, 60 a portion of the truck or wagon on which the apparatus is mounted is shown at A. B is the drum of a concrete mixer of the revolute drum type, and C the discharge chute of the mixer by means of which the concrete, when mixed, is delivered from the drum. D is a distributing trough which is preferably pivotally mounted at its inner end on the truck A in such manner that its angle of inclination, with respect to the 65 ground, may be varied to the extent, for example, indicated by line a in Fig. 1, and so that it may be swung laterally within certain limits indicated by the lines b, b in Fig. 6. E is a hopper which receives concrete from the discharge chute C of the mixer and delivers the same into trough D. F is an endless double chain provided with 70 paddles or buckets G by means of which the concrete is carried along through the distributing trough. The bottom of the trough is formed at intervals with discharge openings adapted to be closed by gates H. It terminates in a discharge chute J and by swinging the trough on its vertical pivots 75 the concrete from the mixer may be delivered at any desired point within the range of the machine. The trough D is secured between a pair of angle irons 25 which are attached to angles 26 secured at their inner 80 ends to castings 27 and at their outer ends to plates 28. Below angles 26 is another pair of angles 29 likewise secured to castings 27 and to the plates 28. A truss frame 30 is attached to the plates 28 and by means 85 of members 31 to the angles 26, 29. The truss frame is provided at its upper end with plates 32 adapted to be secured by a bolt 33 to plates 34 on the uprights 35 (Fig. 3). The castings 27 are connected by pivot pins 36 to 100

lugs 37 on a casting 38 to opposite sides of which the uprights 35 are secured. The casting 38 is formed with a vertical bearing 39 by means of which the casting is pivoted 5 on a stud 40 projecting upwardly from the flooring 41 of the truck. Secured to the upper ends of uprights 35 is a plate 42 pivoted by means of pivot pin 43 to a plate 44 on a framework 45 rigidly mounted on the 10 truck A. The pivot points provided by pin 43 and stud 40 are, of course, in line with each other. The structure carrying the distributing trough D may, therefore, swing sidewise on pivots 40, 43, the limit of movement being indicated by lines b, b in Fig. 6. The portion of the trough supporting structure composed of the truss frame 30, casting 27 and the parts rigidly connected therewith may be turned about pivot 36 so 20 as to change the inclination of the trough, the limit of upward movement of the trough being indicated by line a in Fig. 1. In order to hold the trough at any desired inclination the plates 34 are provided with 25 a plurality of perforations 46 for the bolt 33.

The pair of chains F to which the buckets G are attached, are supported upon and driven by large sprockets 47 at the inner end 30 of the trough which are fixed to shafts 48 mounted in bearings on the castings 27 and sprockets 49, at the outer end of the trough which are loose upon a shaft 50. The position of the shaft 50 may be adjusted so as to 35 give the chain F the proper tension by means of set screws 51 which extend through the ends of castings 52 and bear against the extremities of the shaft 50; the castings 52 being secured to plates 28 and being slotted 40 for the ends of shaft 50.

The buckets or paddles G are preferably made of sheet metal and concave on the side engaging the concrete. They preferably fit rather closely into the trough D. They are 45 attached to cross slats 53 secured by angle pieces 53^a to the chains F.

The chains F, which, in effect, constitute a single member, are preferably driven by a driving train connected with the mechanism 50 for revolving the mixer drum B. The driving train for the chain is disposed with respect to the vertical pivots of the trough supporting structure so that the trough may be shifted laterally without disconnecting 55 the chain driving mechanism. The drum B of the concrete mixer is shown as provided with a circular rack or pinion 54 meshed by a pinion 55 on a shaft 56 which may be driven by any suitable motor (not 60 shown). 57 is a shaft mounted in bearings 58 on the floor of the truck and having keyed thereto a bevel pinion 59 which is meshed with a bevel pinion 60 turning on an extension 61 of stud 40. Mounted on the

casting 38, which, it will be understood pivots on stud 40, is a shaft 62 having keyed to one end thereof a pinion 63 meshing with pinion 60 and on the other end a bevel pinion 64 meshing with a bevel pinion 65 on a shaft 66 turning in bearings 67 on the casting 38. On one end of shaft 66 is a sprocket wheel 68 connected by a belt 69 with a sprocket wheel 70 on the shaft 48 which carries the sprocket 47 for chain F. Shaft 57 has keyed thereto a sprocket wheel 71 70 driven by a chain 72 from a sprocket 73 loose on shaft 56 but adapted to be engaged therewith by a clutch 74 of any suitable construction. The pivots 36, 66 are so close together that the slight change of inclination 80 of the trough does not interfere with the proper operation of the driving chain 69.

In order to prevent the buckets from being injured by being brought into contact with too large a mass of concrete in the feeding 85 hopper, the concrete is not fed from the hopper directly into the inner end of the trough B but is deflected to the sides of the hopper when falling into the same from discharge chute C of the mixer, and enters the trough 90 B through openings in the sides thereof. To this end a deflecting casting 75 is arranged in the hopper E. The casting has a plow like point 76 directed toward discharge chute C. The surface 77 of the casting 95 which faces toward the trough and chain F is curved transversely with a curvature corresponding to that of the buckets G and the lower portion of the same is also curved on lines concentric with the axis of sprocket 47 so that this portion of the casting provides, in effect, an upwardly curved continuation of the trough D through which the buckets 100 G move when passing around sprocket 47. The hopper tapers down toward the trough 105 D so that a spout portion 78 is provided of the same cross sectional configuration as the end of the trough. This spout alines with the trough as shown in Fig. 4 and, in effect, forms a continuation of the trough. The 110 spout portion of the hopper is formed on the side with openings 79 to which lead passageways 80 on opposite sides of the deflecting member 75, these passageways being preferably covered by flanges 81 which, at their lower extremities, aline with the horizontal flanges of the angles 26 to which the trough D is secured; tracks 82 for the chain F being laid on the angles 26 and flanges 81. By this arrangement a limited amount of 115 concrete is engaged by the buckets as they move around sprocket 47. Moreover, as the buckets work over the curved surface 77 and between openings 79 there is no danger of stones, or such like hard objects, being 120 caught between the buckets and the walls of the space in which the buckets operate and causing an injury to the apparatus. 125

The discharge openings in the trough D are formed preferably by making the trough in sections and spacing the sections apart. 83, 84 in Fig. 4^a indicate two of such sections. The gates H for closing the discharge openings are, in effect, trough sections. They are preferably provided along their upper edges with strips 85 which project beyond the gates at one end and are pivoted to the adjacent trough section, 83, for example, by rivets 86. The arrangement is preferably such that when the gate is in its closing position the end thereof nearest the outer or discharge end of the trough aligns 10 with the adjacent trough section, 84 for example, (Fig. 4^a) while the other end overlaps the next trough section 83. Secured to the strips 85 are depending arms 87 supporting and rigidly connected to a cross rod 88 to the ends of which are pivoted links 89, the upper extremities of the links being pivoted to the arms of bell cranks 90 affixed to opposite ends of a shaft 91 preferably mounted in supports 92 attached to the 25 angles 26, 29. The long arms 93 of the bell cranks serve as handles for manipulating the gates. The full lines in Fig. 4^a show the gate and its operating mechanism in the closed position. The dotted lines indicate 30 the gate in its open or lowered position. In this position it forms a chute for the material discharged through the opening between sections 83, 84 of the trough.

The trough is preferably open at its outer 35 end and provided with a discharge chute J supported at its outer end by a strap 94. The slant of the discharge chute J begins inwardly of the axis of sprocket 49 so that the material discharged through the open 40 end of the trough clears the buckets before the latter begin to tilt upwardly. This arrangement prevents the buckets from throwing the material out of the trough. It is desirable to give the distributing trough a 45 fixed position during the distribution of the material along any given line, changing said position by swinging the trough on pivot 40, as occasion requires. To this end the casting 38, which supports the distributing 50 trough and associated mechanisms, is formed with a lug 95 having a vertical perforation to receive a locking bolt 96 adapted to enter any one of a series of perforations 97 in an extension 98 of the flooring of the truck. 55 The lug is formed with a clevis 99 in which is arranged a forked lever 100 mounted on a rock shaft 101, the fork of the lever engaging a cross pin 102 arranged in a slot 103 in the pin 96. The rock shaft 101 60 carries on opposite ends levers 104 to which is attached a cord 105 running through guides 106 on the members 31 of the supporting structure for trough D, anchored to staples 107 on plate 28. By this arrange-

ment the distributing trough may be locked 65 in the desired angular position by a workman standing on either side of the trough and at any point along the same.

The purpose of the modified construction shown in Fig. 7 is particularly to eliminate 70 the somewhat heavy and cumbersome frame member 35 forming part of the apparatus above described. In the construction shown in Fig. 7 the supporting frame 30' for the distributing trough D' is pivoted directly 75 to the framework 45' by a vertical pivot pin 43'. The casting 27' is likewise pivoted to the flooring 41' of the truck, and in addition is provided with rollers 111 which run upon an arcuate track 112 on the truck. In 80 other respects this apparatus may be constructed the same as that previously described.

In Fig. 8 I have illustrated another modification in which a screw conveyer K is employed instead of the chain F and buckets G for propelling the material through the distributing trough designated D² in this figure. The mixed concrete is delivered from the discharge chute C to a hopper E² which 85 opens at the bottom into the trough D². The trough D² is secured to a casting 114 revolvably mounted on a pivot 115 fixed to the flooring 116 of the supporting truck. On the end of shaft 117 of the conveyer is a bevel pinion 118 which meshes with a bevel pinion 119 on an extension 120 of pivot 114. The pinion 119 is meshed by a bevel pinion 121 carried on a shaft 122 corresponding to shaft 57 in the machine shown in Figs. 1 to 6 inclusive. 90 The shaft carrying a sprocket wheel 123 is driven by a belt from the driving shaft of the drum as in the machine hereinbefore described. The bearings of shaft 117 are protected by a felt packing 124 and cap 125. 95

While I have described my invention in certain preferred embodiments, it will be understood that further modifications might be made without departure from the invention. Therefore I do not wish to be understood as limiting the invention to the particular constructions, arrangements and devices above specified except so far as the 100 claims are expressly so limited.

I have used the term "chain" to denote the endless flexible member by means of which the buckets G are moved through the trough. It will be realized, however, that a belt would be an equivalent for the chain, although for obvious reasons, a chain is preferable. 110

I claim:

1. In apparatus of the character described, the combination of a distributing trough consisting of trough sections spaced apart so as to provide discharge openings at intervals, trough like gates, and means for supporting the same either in position 115

120

125

- to close the openings between said trough sections or in an inclined position to permit the discharge of concrete through said openings, the edges of said gates remote 5 from the point at which the concrete enters the trough being flush with the edges of the adjacent trough sections respectively when said gates are in closed position and the opposite edges of the gates overlapping 10 the edges of the trough sections engaged thereby; said last-mentioned edges being adapted to assume a position under the trough when the gates are in their open position.
- 15 2. In apparatus of the character described, the combination of a distributing trough having a discharge opening, a trough like gate pivoted to the trough and provided on opposite sides with depending 20 arms, a cross rod fixed to said arms, bell cranks pivotally mounted on opposite sides of said trough, and links connecting said cross rod and bell cranks all arranged so that by manipulation of the bell cranks the 25 gates may be held either in an inclined position below said discharge opening or in position to close said opening.
3. In apparatus of the character described, the combination of a distributing 30 trough having a discharge opening, a trough like gate pivoted to the trough and provided on opposite sides with depending arms, a cross rod fixed to said arms, bell cranks pivotally mounted on opposite sides 35 of said trough, and links connecting said cross rod and bell cranks all arranged so that by manipulation of the bell cranks the gates may be held either in an inclined position below said discharge opening or in 40 position to close said opening with the edge of the gate remote from the point at which the concrete enters the trough flush with the adjacent edge of the trough and the opposite edge of the gate overlapping the 45 trough.
4. In apparatus of the character described, the combination of a distributing trough, a feed hopper at one end of said trough, means for conveying the material 50 through said trough comprising an endless chain, buckets thereon adapted to move through said trough, and a deflecting member in the hopper which causes the material to enter the trough through the sides 55 thereof.
5. In apparatus of the character described, the combination of a distributing trough, a feed hopper at one end of said trough, means for conveying the material 60 through said trough comprising an endless chain, buckets thereon adapted to move through said trough, and a deflecting member in the hopper which causes the material to enter the trough through the sides there-

of, said member formed with a curved surface along which the edges of the buckets move when picking up material entering said trough.

6. In apparatus of the character described, the combination of a distributing trough, a feed hopper at one end of said trough, means for conveying the material through said trough comprising an endless chain, buckets thereon adapted to move through said trough, and a deflecting member in the hopper which causes the material to enter the trough through the sides thereof, said member formed with a curved surface along which the edges of the buckets move when picking up material entering said trough, at an oppositely disposed deflecting point.

7. In apparatus of the character described, the combination of a distributing trough, a feed hopper at one end of the trough, sprockets arranged at opposite ends of the trough, an endless chain, buckets thereon adapted to move through said trough, and means whereby the material from the hopper is fed into the trough at the sides in advance of the sprocket at the inner end thereof.

8. In apparatus of the character described, the combination of a distributing trough, sprockets arranged at opposite ends of the trough, an endless chain and buckets adapted to move the material through said trough, and means for feeding the material into the trough through the sides thereof in advance of the sprocket at the inner end thereof.

9. In apparatus of the character described, the combination of supporting means, a distributing trough pivoted thereon so as to permit the vertical inclination of the trough to be varied, formed with a series of discharge openings and with a discharge chute at its outer end, sprockets arranged above said trough at opposite ends thereof, a chain carried by said sprockets, a plurality of buckets on said chain, gates separately operable to close said discharge openings, driving mechanism on said support for driving the chain which accommodates itself to different angular positions of the trough, a hopper discharging into said trough, and a deflecting device in said hopper whereby the material in the hopper enters the trough through the sides thereof.

10. In apparatus of the character described, the combination of supporting means, a distributing trough mounted thereon formed with a series of discharge openings and with a discharge chute at its outer end, sprockets arranged above said trough at opposite ends thereof, a chain carried by said sprockets, a plurality of buckets on said chain, gates separately operable to close said

discharge openings, driving mechanism on said support for driving the chain which accommodates itself to different angular positions of the trough, a hopper discharging 5 into said trough, a deflecting device in said hopper whereby the material in the hopper enters the trough through the sides thereof,

and means whereby different inclination vertically may be given to said trough.

ALFRED D. MOSBY.
